UNITED STATES PATENT OFFICE

106,924

DESIGN FOR A BOLERO JACKET

Charles Lewis, New York, N. Y.

Application September 30, 1937, Serial No. 71,882

Term of patent 3½ years

To all whom it may concern:

Be it known that I, Charles Lewis, a citizen of the United States of America, residing in New York city, in the Borough of Manhattan, county and State of New York, have invented a new, original, and ornamental Design for a Bolero Jacket, of which the following is a specification, reference being had to the accompanying drawing, forming part thereof, wherein,

The grouped figures on either side of the front bolero, represent superimposed appliqués.

I claim:

The ornamental design for a bolero jacket, substantially as shown and described.

CHARLES LEWIS.
